UNITED STATES PATENT OFFICE.

EDWARD E. KILBOURN, OF NEW BRUNSWICK, NEW JERSEY, ASSIGNOR
TO THE KILBOURN KNITTING MACHINE COMPANY.

MANUFACTURE OF SEAMLESS HOSIERY.

No. 821,944.

Specification of Letters Patent.

Patented May 29, 1906.

Application filed January 30, 1903. Serial No. 141,128.

To all whom it may concern:

Be it known that I, EDWARD E. KILBOURN, a citizen of the United States, residing at New Brunswick, in the county of Middlesex and State of New Jersey, have invented certain new and useful Improvements in Manufacture of Seamless Hosiery; and I do hereby declare the following to be a full, clear, and exact description of the invention, such as will enable others skilled in the art to which it appertains to make and use the same.

My present invention relates to the manufacture of seamless hosiery, and more particularly to the manufacture of seamless lace or open-work stockings, in which a solid plain-knit portion precedes the lace or open-work of the stocking.

In the drawings, Figure 1 is a view of a stocking having sections of open-work at two different parts of the same. Fig. 2 is a view of a half-hose having lace-work around the leg with lace-work extending down upon the foot. Fig. 3 is a detail of the loops as they appear at the point where the loops of two needles are cast off to form the lace stitch.

In making the class of stockings described it is desirable to have a solid plain-knit portion at the top of the leg of the stocking or full-length hose for the welt or hem, and in the half-hose it is desirable to knit a greater or less portion just below the ribbed top. When the stocking or half-hose is knit in this way, at a certain point it is necessary to drop certain stitches to form the lace-work, and it then becomes necessary to secure the loop thrown off in order that they may not ravel back into the plain knitting.

In case the point of beginning the open or lace work is immediately below the welt or line of stitching securing the hem of the stocking the welt or hem will hold the drop-strokes from opening out beyond this point.

If the open or lace work is to begin at any point or points below the welt or hem of a stocking or below the ribbed top of a half-hose, the cast-off loops may be secured by a hand-crocheting of such loops or by a line of stitching sewed by hand or machine. Either of these modes will effect the result desired; but such drop-strokes may also be secured by causing certain of the needles to be operated to knit tuck-strokes for one or more courses immediately preceding the casting off

of the loops. This latter method is the one I prefer, as it can be effected by the knitting-machine and during the knitting of the stocking. In case plain knitting is resumed at any part or entirely around the stocking and a further section of open or lace work is begun the drop-strokes can be again secured in the same manner.

In the drawings, A indicates the leg, and B the foot, of the stocking. a indicates the lace-work-strokes, and b the plain-knit portions for joining the toe. b' indicates a band of plain knitting around the ankle above the heel.

In Fig. 3 I have shown, in an enlarged view, the loops as they appear at the point of casting off the loops of two needles and at the point where certain needles have just knit tuck-strokes to hold the previous plain knitted work. Such stitches are indicated by the reference-letter c. In this instance I have shown a tuck-stitch on each side of the dropped stitch; and this arrangement is found to prevent the dropped loops from raveling back into the plain knitting. It is not necessary to use a tuck-stitch on each side of the dropped stitch; but this is my preferred mode of proceeding. I have shown these tuck-strokes in two courses; but they may be in a greater number of courses or they may be made only in a single course, as may be preferred.

In Fig. 1, d indicates a line of hand or machine sewed stitching to secure the loops cast off.

What I claim, and desire to secure by Letters Patent, is—

1. The herein - described machine - knit seamless stocking having open-work with drop-strokes therein, a solid plain-knitted portion preceding such open-work, the dropped strokes preceding the open-work being secured from raveling back into the plain knitting.

2. The herein - described machine - knit seamless stocking having alternating plain and lace or open-work portions and having tuck-strokes in one or more courses just preceding the change from plain to open-work or lace-work knitting.

3. A machine-knit seamless stocking having a plain-knitted portion at the top of the stocking, a plain-knitted portion at the toe

of the stocking, and a portion having open-work with drop-stitches therein between said plain portions and tuck-strokes for securing the stitches to begin such open-work, substantially as described.

4. A machine-knit seamless stocking having a plain-knitted portion at the top, an open-work portion following the same having drop-strokes therein, and tuck-strokes

securing the stitches dropped to begin the 10 open-work, substantially as described.

In testimony whereof I affix my signature in the presence of two witnesses.

E. E. KILBOURN.
